UNITED STATES PATENT OFFICE.

CYRILL ENGALITCHEFF, OF BALTIMORE, MARYLAND.

SANITARY SEAT COVER.

Application filed November 19, 1927. Serial No. 234,478.

This invention relates to seat covers adapted for use on the seats of water closet bowls to protect the user from contamination by matter left on the seat by previous users.

5 Covers of this general kind have heretofore been commonly made of relatively thick paper. Generally, they are removed from the seat after use and thrown into a basket, but are often left on the seat or removed by

10 the user and thrown on the floor.

According to my invention I make the cover of thin tissue paper of such shape and size that it may be easily applied to the seat and when the seat is occupied will protect the user from contamination at all points and will also prevent the splashing of water when solid matter is dropped into the bowl. The construction is also such that when the user rises from the seat and then turns on

20 the flush water the cover will be at once automatically drawn into and washed out of the bowl into the drain. Other features of the invention will be hereinafter explained.

Seat covers made in accordance with my 25 invention may be folded into a compact packet and several such covers may be carried in a pocket, suit case, slot machine, or other receptacle.

In the accompanying drawings:

30 Figure 1 is a perspective view of a water closet bowl with one of my improved sanitary seat covers applied. Parts of the bowl are broken away in order to show certain parts of the cover which would otherwise be hidden;

35 Figure 2 is a plan view of a blank from which the cover is formed;

Figure 3 is a plan view of the blank after it is folded and arranged for use;

40 Figure 4 shows a section on the line 4, 4, of Figure 3;

Figure 5 is a sectional view showing how a part of the cover is arranged below the seat-covering part; and

45 Figure 6 is a perspective view of the cover folded to a convenient size and shape for carrying in a pocket or other receptacle.

Blanks for the covers are shaped in the manner illustrated in Figure 2. These may 50 be cut in quantities by a die from a pile of thin tissue paper of the proper grade.

Each blank comprises a central portion *a* and front and rear arms *b*, *c*, the rear arm *c* being slightly longer than the front arm *b* for a purpose hereinafter explained. The front arm *b* connects at its outer end with

two side members *d*, *e*, which together form a semi-circular cover member for the front portion of the seat. This member is formed with a flap *f* designed to extend over the front of the seat. The rear arm *c* is connected to a rear member having curved side members *g*, *h*, designed to cover the rear portion of the seat.

A blank such as shown in Figure 2 is 65 formed into a seat cover by bringing the ends of the side members *d*, *e*, *g*, *h*, together and securing them by glue or by other suitable means. When in the condition shown in Figure 3 the cover may be applied to 70 the seat of a closet bowl or it may be folded in the manner shown in Figures 4 and 6. When in the latter shape it may be conveniently carried in the pocket or otherwise carried.

When ready for use the cover is unfolded and placed on the closet seat in the manner shown in Figure 1. It will be observed that the top of the seat is completely covered and that the flap *f* extends over the front 80 of the seat to afford additional protection. The central member *a* is suspended from the top member by the arms *b* and *c*. The front arm *b* being relatively short will assume a nearly vertical position and protect the front 85 portion of the inside of the bowl. The rear arm *c* inclines from top to bottom forwardly and is slack or crimped. This rear arm protects the rear portion of the inside of the bowl in an obvious manner.

90 When the cover is thus adjusted and the seat is occupied the user is thoroughly protected against contamination.

When solid matter is dropped into the bowl it strikes the central member *a* and is 95 supported thereby. The weight of this solid matter causes the member *a* to tilt, as indicated by dotted lines in Figure 5, the rear arm *c* being at this time straightened.

When the user rises from the seat and turns on the flush water the cover will be drawn bodily into the bowl and will be washed out of the bowl into the drain with the solid matter.

100 Experience has demonstrated that by using thin tissue paper for the cover and giving it the shape hereinbefore described contamination is avoided, the cover always leaves the bowl with the flush water, and no stoppage or clogging of the drain occurs.

110 It will be observed that the central member *a* is considerably wider than the adja-

cent portions of the arms *b* and *c* thus, without unduly increasing the size and weight of the cover as a whole, enabling the portion *a* to float to better advantage, to prevent 5 splashing more effectively and to present a relatively large but light body to be acted upon by the flush water and by the suction which takes place when the flush water is in action.

10 By making the rear arm *c* longer than the front arm *b* the latter is caused to assume a nearly vertical position when the cover is applied to the seat thus causing said arm to come closer to the front of the bowl and better protect it.

By making the rear arm longer it will assume a crimped or corrugated condition when in use as indicated in Figs. 1 and 5, so that when the part *a* sinks or is weighted 20 initial strain on the arm *c* is relieved and danger of breakage is reduced.

It will be observed by reference to Figure 2, which shows the blank from which the cover is made, that the central member *a* and 25 the arms *b*, *c* hold the inner ends of the members *d*, *e*, *g*, *h* a considerable distance apart so that when the ends of the arms are brought together and secured to each other, the central member *a* and the arms *b*, *c* will 30 be properly depressed as indicated in Figure 5 and also in Figure 1 thus holding the central member in a horizontal plane on the

top of the water with the front arm nearly vertical while the rear arm is crimped and inclined. When the flush water is turned on 35 and suction takes place, the rear arm straightens out as indicated in Figure 5 and then a pull is exerted on both arms *b* and *c* which causes the thin light cover to disappear. 40

I claim as my invention:

1. A blank for a cover for a water closet seat comprising a central member, a front member having curved side portions, a rear member having curved side portions, the 45 inner ends of which are separated a material distance from the inner ends of the other curved portions and front and rear arms connecting the front and rear members with the central member. 50

2. A blank for a cover for a water closet seat comprising a central member, a front member having curved side portions, a rear member having curved side portions, the 55 inner ends of which are separated a material distance from the inner ends of the other curved portions and front and rear arms of different lengths connecting the front and rear members with the central member. 60

In testimony whereof, I have hereunto subscribed my name.

CYRILL ENGALITCHEFF.
